(57) **CLAIM**

What is claimed is the ornamental design for accessories of radiotherapy equipment, as shown and described.

DESCRIPTION

FIG. 1 is a front view of accessories of radiotherapy equipment, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

The broken lines show portions of the accessories of radiotherapy equipment and form no part of the claimed design. The shading lines shown in the drawings represent the approximate three-dimensional contour of the design, and are not intended to indicate surface decoration.
